CONTAINER VALVE

Stephen D. Hartog, Normandy, Mo.

Application June 21, 1937, Serial No. 149,353

10 Claims. (Cl. 221—60)

This specification, aided by the accompanying drawing, discloses certain improvements in container valves, more particularly, to valves adapted for use on collapsible tubes.

The purpose and use of container valves, caps, closures, and like devices employed to open and close the discharge aperture of tubes has been abundantly described in extant literature, and further reiteration therefore would only be additional surplusage, except, to briefly summarize; certain containers, collapsible tubes and the like are employed to vend plastic materials such as tooth-paste, vaseline, and various other materials including medicinals having a paste-like consistency, and when the contents of such tubes are exhausted, they are discarded having no further serviceable value.

The design and construction of the character of valves thus described must therefore be of such a character that their all inclusive production cost approximates as near as is practically possible their minimum material cost, and the quantity of material used in the make-up of the valve should be within scant limits.

The primary object, therefore, of the invention herein described and illustrated, is to provide a container valve designed and constructed in such a novel, economical, and practical manner, that all of the difficulties and incapacities encountered in prior art types of container valves are surmounted.

To such ends the invention herein described and illustrated provides:

A container valve having few parts in its construction.

A container valve closure having oscillatory movement upon a pivot and bearing of novel construction.

A container valve having a closure capable of being sustained, supportedly in any suitable position within the sweep of its oscillatory movement.

A container valve having resiliently yieldable lock engaging means.

A container valve in which all of its parts are so designed and constructed that they are capable of production by means of die-forming processes, thus insuring economical production, accurate duplication, and indefinite reproduction.

For the purpose more clearly to understand the expressed objects, and other attending objects, of the container valve herein described and illustrated, the following description is given, and by aid of the accompanying drawing it is discernible:

Fig. 1 is a plan view of the container valve shown in mounted position upon a tube.

Fig. 2 is a view in cross-section on line 2—2 Fig. 1, illustrated as in mounted position upon the neck portion of a container.

Fig. 3 is a side view in elevation of the container valve shown mounted upon a fragmentary portion of a container.

Fig. 4 is a plan view of an integrally unitary aperture slug.

Fig. 5 is a cross-section view on line 5—5, Fig. 4.

Fig. 6 is a plan view of a fabricated washer.

Fig. 7 is a cross-sectional view thereof on line 7—7.

The parts constituting the container valve are herein designated numerically and in the order of which 10 designates a portion of a container body denominated a collapsible tube. Formed on the apertured discharge end of the tube 10 is an apertured neck 11, having at the base thereof a ledge 12 on which there is a surface 13 providing a shoulder. Mounted on the apertured neck 11 and having a bearing upon the surface 13, is that of a die-formed integrally unitary metallic slug 14 having an aperture 15, the aperture 15 being sized to fit snugly on the neck 11. Within the surface surrounding the aperture 15 there is a chamfer 16, and into which chamfer a rim of metal 17 is spun to secure the slug 14 to the neck 11 of the tube. Within the body of the slug 14, a depression 18 is formed by punching a portion 19 of the body of the slug only part way through; thus, a depression is formed in one surface and a projecting portion 20 is expressed upon the opposite surface of the slug. Extending laterally from the body of the slug 14 are limbs 21 and 22 rectangular in form as and when punched from flat metal, and designed to provide bearings. Within a face end surface midway the extremities of the projecting limbs 21 and 22, an indentation 23 is formed. The discharge aperture 24 of the tube is provided with a closure 25, having projecting portions 26 and 27, which portions are bent to form journal bearings adapted to embrace the limbs 21 and 22 of the slug, and upon which journal bearings the closure 25 has oscillatory movement. The closure 25 is also provided with a projecting tang 28, formed to engage the indentation 23 and to contact spring tensionally therein, whereby the closure is not only prevented from having lateral movement on its bearings, but the closure is also capable of being sustained supportedly in any suitable position in which it may be placed within the sweep of its oscillatory

movement. In order to maintain the closure in its aperture-closing position on the tube, a resiliently yielding locking means is provided by forming angularly bent portions 29 and 30 and in which portions a tab of metal 31 is formed to provide a latch adapted to engage the surface 32 of the slug 14. In order to provide the requisite spring tensional resiliency for the closure locking means, an opening 33, aided by cut-out-notches 34 and 35, is formed in the cover or closure, and between which opening there are stay portions 36 and 37 having a yieldingly resilient spring tensional capacity. The width and length of the stay portions can be properly proportioned to accommodate any desirable resiliency. To prevent leakage of the valve a fabricated disc 38 apertured and having a yieldable compressive capacity is employed. The fabricated disc is positioned within the depression 18 of the slug, and in which position serves to prevent leakage by forming a seal with the cover, due to its yieldability under contact pressure of the closure, when the closure is pressed to a locked engagement with the slug.

The opening of the closure is brought about 25 by finger pressure exerted against the under surface 39 of the bent projection 30.

Having thus described the invention, it is obvious that there is provided a container valve of the character described, and possessed of the advantageous features hereinbefore enumerated as desirable. It is therefore to be understood that the container valve is susceptible of modification in its form, proportions, detailed construction and arrangement of parts without departing 35 from the principle involved or sacrificing any of its advantages.

While the invention has been described in language more or less specific as to structural features, it is to be understood that the invention 40 is not limited to the specific details shown, but that the means and construction herein disclosed comprises the preferred form of several modes of putting the invention into effect and the invention therefore is claimed in any of its forms or 45 modifications within the legitimate and valid scope of the appended claims.

I claim, and desire to secure by Letters Patent of the United States of America, this invention as, in and for:

50 1. In a valve for the discharge end of a collapsible tube, the valve comprising a closure, a support for the closure, the support for the closure comprising a non-resilient slug of flat metal provided with rectangularly formed journal bearing axes, a closure having journal bearings adapted to embrace the rectangularly formed journal bearing axes of the slug, an aperture within the slug dimensioned to fit the neck of the tube, and means to secure the slug to the collapsible tube.

60 2. In a valve for containers, the valve comprising a closure, a support for the closure, the support for the closure comprising an integrally unitary non-resilient metallic slug provided with rectangularly formed journal bearing axes, a centrally formed depression within the slug providing a seat for a sealing gasket for the closure, an oppositely formed projection expressed on the surface of the slug providing a seat for the slug on the tube, a closure having journal bearings 65 operative on the journal bearing axes of the slug, an aperture within the slug dimensioned to fit the neck of the tube and means to secure the slug to the collapsible tube.

70 3. A container valve comprising a non-resilient slug of flat metal adapted to be attached to the

discharge end of the container, an aperture within the slug, integral portions of the slug having rectangular form providing means to support an aperture closure, the aperture closure being provided with journal bearings, the mentioned journal bearings of the closure being constructed and adapted to embrace three surfaces of the rectangular form of the slug supporting means and to over-lap the same in capacity not less than the thickness of the metal of which the slug is made, and means to secure the slug to the discharge end of the container.

4. A container valve comprising a non-resilient slug of flat metal adapted to be attached to the discharge end of the container, an aperture within the slug, integral portions of the slug having rectangular form providing means to support an aperture closure, the aperture closure being provided with bearings, the mentioned bearings of the closure being constructed and adapted to 20 embrace the slug supporting means overlappingly in capacity to the extent of enveloping the supporting means of the slug in excess of the thickness of the metal of which the slug is made, and means to secure the slug to the discharge 25 end of the container.

5. A container valve comprising an apertured slug of non-resilient flat metal adapted for assembly upon the discharge end of a container, the mentioned slug having rectangularly formed 30 portions to provide the sole means by which a valve opening and closing member is supported for operative movement on the mentioned slug, the mentioned valve opening and closing member being provided with portions adapted to 35 embrace the supporting portions of the mentioned slug, whereby the mentioned valve opening and closing member is capable of movement to open and close the aperture of the valve, and means to secure the mentioned slug to the discharge 40 end of a container.

6. As a new article of manufacture, the new article of manufacture comprising a non-resilient metal slug adapted for attachment to the discharge end of a collapsible tube, the metallic 45 slug having an aperture within a portion of the slug off-set from the plain surface of the slug, the off-set portion of the slug being severed from the body of the metal of the slug yet remaining contactingly engaged thereto, thereby 50 forming a depression within the surface of the slug, and an expressed protecting portion formed on the opposite surface of the slug, and the mentioned aperture within the mentioned off-set portion of the slug arranged to provide means 55 by which the mentioned slug is attached to the discharge end of a collapsible tube.

7. As a new article of manufacture, the new article of manufacture comprising a non-resilient metallic slug adapted for attachment to the discharge end of a container, the metallic slug having an aperture within a portion of the slug off-set from the plain surface of the slug, the off-set portion of the slug being severed from the body of the metal of the slug yet remaining contactingly engaged thereto, thereby forming a depression within the surface of the slug and an expressed projection on the opposite surface of the slug, the mentioned slug having marginal portions surrounding the mentioned off-set portion of the slug, the mentioned aperture within the mentioned off-set portion of the slug arranged to provide the means by which the mentioned slug is attached to the discharge end of a container.

8. In a valve for the discharge end of a collapsible tube, a closure for the aperture of the valve, a support for the closure, said support comprising an integrally unitary non-resilient 5 metallic slug provided with portions forming bearings, the slug having an apertured off-set portion forming a depression within the surface of the slug providing a seat for an apertured gasket, an expressed projecting portion on the opposite surface of the slug providing a seat for the slug on the tube, the aperture within the off-set portion of the slug being dimensioned to fit the neck of the tube, and means to secure the slug to the collapsible tube.
- 10 9. A collapsible tube valve comprising a non-resilient metallic slug apertured to provide a collar for the neck of a collapsible tube, portions on the collar to provide bearings, a depression formed within the collar, aperture sealing means seated within the depression formed in the collar, a closure for the discharge aperture of the tube, journal bearings on the closure, the bearings on the closure adapted to embrace the bearing portions formed upon the collar, resiliently 15 yielding means to lock the closure upon the collar, means yieldingly contacting the bearing por-
- tion of the slug apertured collar adapted to sustain the mentioned closure in any open position to which it may be swung, and means to secure the valve to the tube.
- 15 10. A collapsible tube valve comprising a metallic slug apertured to provide a collar for the neck of a collapsible tube, a bearing portion on the collar, a closure for the discharge opening of the tube, journal bearings on the closure, the journal bearings of the closure adapted to embrace the bearing portions formed on the collar, thereby providing means by which the closure has oscillatory movement on the respective bearings thus provided, sealing means for the closure, the sealing means being yieldingly susceptible of compression under the contacting pressure of the closure, yielding means adapted to lock the closure to the collar, and contact means adapted to maintain the closure in any position in which it may be positioned within the 20 sweep of its oscillatory movement, the mentioned contact means being operative within a niche formed in the slug thereby preventing lateral displacement of the closure.

25 STEPHEN D. HARTOG.
